CONTROL FOR ELECTRIC ADVERTISING SIGNS

Filed Sept. 11, 1929

BY

23 Edward M. Rosenfield
Louis Barnett
ATTORNEY

UNITED STATES PATENT OFFICE

EDWARD M. ROSENFIELD, OF NEW YORK, N. Y.

CONTROL FOR ELECTRIC ADVERTISING SIGNS

Application filed September 11, 1929. Serial No. 391,749.

This invention relates to an electrically operated sign equipment for motor vehicles and more particularly is directed to an advertising installation for taxicabs or the like, in which the sign and the taximeter of the vehicle are cooperatively interlocked for concomitant service.

In practicing this invention it is contemplated to mount an electrically operated sign in the passenger compartment of the taxicab and to provide a positive fool-proof installation whereby the sign is made operative only during the time the manual control of the taximeter is in position to cause the latter to register.

One object of the invention is to provide an improved electrically operated sign installation of the character described which shall interlock with the taximeter in a novel manner whereby the sign is operated only while the taximeter is registering a fare.

Another object is to provide an installation of the character described which can be readily applied to taximeter vehicles of standard construction without requiring extensive alterations or changes of the standard equipment.

A further object of the invention is to provide in an installation of the character described, a simple interlocking mechanism for engaging with the "flag" or the like manual control of a taximeter which shall cause the chauffeur the least inconvenience yet positively operate the electric sign to function in a desired sequence concomitantly with said "flag" control.

Other objects of this invention will in part be obvious and in part hereinafter pointed out.

The invention accordingly consists in the features of construction, combination of elements and arrangement of parts which will be exemplified in the construction hereinafter described and of which the scope of application will be indicated in the following claims.

In the accompanying drawing in which is shown one of the various possible illustrative embodiments of this invention,

Fig. 1 is a fragmentary side elevational

view of a vehicle, partly in section, showing an installation embodying the invention.

Fig. 2 is a cross-sectional view taken in lines 2—2 in Fig. 1.

Fig. 3 is an elevational view, partly in section, showing in detail the electric switch means interlocking with the "flag" control of taximeter, and

Fig. 4 is a top view of the detail shown in Fig. 3.

Referring in detail to the drawing, 10 denotes a fragmentary portion of a taxicab equipped with a taximeter 11 and provided with an accessory to embody the invention. The taxicab and meter may be of any well understood construction, the taximeter being positioned adjacent the chauffeur's seat 12 within convenient reach for manipulating a manual control means, such as the pivoted "flag" member 13. The latter is adapted to cause the meter 11 to register when swung in down position, shown in dotted lines in Fig. 3, and indicating the non-registering or "vacant" position when upstanding as shown in full lines in Figs. 1, 2 and 3. The vehicle 10 is provided with the usual compartment 14 in which the passenger rides.

Adjacent the wall partition of the compartment 14, back of the driver's seat 12 and preferably adjacent the top 15 of the vehicle there is mounted a sign 16. Said sign may be electrically lighted by suitable means, such as the lamp 17, and when used for an advertisement display may have a plurality of posters, (not shown) illuminated by said lamp 17. Said posters may be movably mounted in the casing of the sign to register with the window opening 16^a by the suitable electrically operated mechanism, such as for example described in detail in my Patent 1,760,644, May 27, 1930. As here shown, the casing of the sign 16 is hung on a pair of pivoting brackets 18 which are secured to the roof cross-braces 19.

20 denotes a storage battery which provides a reserve source of electric power to the vehicle power plant equipment for lighting and other purposes, said battery being connected with the charging outfit of the vehicle power 100

plant (not shown) in a well understood manner.

Circuit wires 21 interconnect the electrically operated portion of the sign 16 with said storage battery 20 and a switch 22 is interposed in the circuit between the battery and the sign for controlling the power received from the battery by the said electric operating parts of the sign. Switch 22 may be housed in a casing 23 positioned adjacent the taximeter 11. Said switch may be of the toggle type having the end of its handle 24 pivotally engaged, as at 25, with the lower end of a lever bar 26, the latter being mounted in said casing 23 in any suitable manner for swinging movement about the fulcrum 27. The upper end of said lever bar may be pivoted, as at 28, to one end 29^a of a horizontally disposed barrier member 29. The portion of said member adjacent said end 29^a is mounted for sliding in and out of the casing 23, and the portion 29^b of said member extending outside said casing is provided with an elongated slot 29^c through which the "flag" control 13 extends.

From the foregoing description and Figs. 3 and 4 of the drawing it is apparent that swinging the "flag" control 13 from its "upstanding" position, shown in full lines, in Fig. 3 to its "down" position shown in dotted lines, and sliding the barrier member 29 into the casing will throw the handle 24 of the toggle switch 22 from its "off" position shown in full lines into its "on" position shown in the dotted lines. The switch parts when in "on" position feeds power through the circuit to the sign from the battery, concomitantly as the taximeter registers. It is thus seen that a passenger in the compartment 14 with the meter registering will observe the electrically illuminated sign 16. When the passenger vacates the compartment the chauffeur swings the "flag" control 13 from its "down" position, shown in dotted lines in Fig. 3, to its "upstanding" position to make the taximeter non-registering. In so doing he will slide the barrier member 29 out of the casing and thereby swing the handle of the toggle switch 22 from the "on" position shown in the dotted lines (Fig. 3) to the "off" position shown in the full lines. It should be noted that the slot 29^c of the barrier member is so proportioned and positioned that the "flag" control 13 cannot be swung into its full "upstanding" position without withdrawing the barrier member and swinging the handle of the toggle switch 22 to its "off" position as shown. Nor can the "flag" control 13 be swung to its "down" position without sliding the barrier member into the casing 23 and swinging the handle of the toggle switch 22 to its "off" position.

The toggle switch 22 is of the standard "snap" type, therefore, the switch handle 24

move to either the position shown in the full lines or that shown in dotted lines. This arrangement of elements in the combination provides a positive means for causing concomitant operation of the "flag" control and the switch 22.

To further make the installation fool-proof, a bell-crank 30 may be pivoted, as at 31, in the casing 23, one arm 30^a of the crank being terminated within a dog for engaging in a notch 26^a provided in the lever bar 26, while the other arm 30^b of crank is extended through an opening 23^a in the casing and projects in the path of movement of the "flag" control 13. The latter when swung down is adapted to depress the arm 30^b and to swing the dog of the arm 30^a to engage in the notch 26^a. A tension spring 31 may be provided between the housing 23 and the arm 30^b for normally retaining the latter in its extreme upwardly swung position to disengage dog from the notch 26^a. By providing the bell-crank 30, as above described, the switch 22 is positively locked and retained in its "on" position while the "flag" control 13 is swung down, and the barrier member 29 cannot be manipulated or accidentally moved until the "flag" control is raised.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. In a motor vehicle equipped with a manually controlled taximeter, an electric sign, of a switch for controlling the operation of said sign, and manually operated means detached from and interlocking with the manual control of said taximeter for actuating the switch.

2. In a motor vehicle of the character described, equipped with a taximeter having a movable manually controlling member, an electric power source, and a sign connected in circuit to receive power from said source, of means for opening and closing said circuit during the operation of said member, said means including a barrier displaceable from the path of movement of said member and for the purpose described and specified.

3. In a vehicle installation of the character described, equipped with a taximeter having a manual control, an electric power source,

and a sign connected in circuit with said source, of manual actuated means for locking said manual control with said circuit whereby the latter may be opened and closed during the actuation of said control.

4. In a vehicle installation of the character described, equipped with a taximeter having a movable member manually operated for selectively making the taximeter operative and 10 inoperative, an electric power source, and a sign connected in circuit with said source, of a switch for opening and closing said circuit, said switch including a barrier interlocking with said member displaceable from the path of movement of the latter as and for the purpose described and specified.

5. In an installation of the character described, the combination with a taximeter having a movable "flag" register control, of 20 an electric switch adapted to connect in circuit with a power source an electric sign, and a barrier means interlocking with the "flag" control whereby said means is displaced from the path of the "flag" control for closing the sign circuit to said source while moving said control for causing the taximeter to register.

6. In an installation of the character described, the combination with a taximeter having a movable "flag" register control, of 30 an electric switch adapted to connect in circuit with a power source an electric sign, a barrier member cooperating with the "flag" control whereby said member when displaced from the path of the "flag" control closes the switch circuit, and means cooperating with said member for retaining said switch in circuit closing position as long as said "flag" control causes the taximeter to register.

7. In an installation of the character described, the combination with a taximeter having manual control means for throwing the latter in and out of operation, of an electric switch adapted to connect and disconnect an electric sign from a power source mounted adjacent the exterior of said taximeter, means for concomitantly operating said switch and control means, and means for releasably locking the switch in effective position against movement when the taximeter 50 is registering.

8. In an installation of the character described, the combination with a taximeter having manual control means for throwing the latter in and out of operation, of an electric switch adapted to connect and disconnect an electric sign from a power source mounted adjacent the exterior of said taximeter, means for concomitantly operating said switch and control means, and means for releasably locking the switch in effective position against movement when the taximeter is registering, said locking means being actuated by said control means.

9. In a motor vehicle equipped with a taximeter having a manual control, a storage

battery mounted on said vehicle, and an electrical sign connected in circuit with said battery, of a switch for controlling said circuit, said switch being positioned a spaced distance from the taximeter, and a linkage 70 interconnecting the switch with said manual control whereby the taximeter and said sign are concomitantly operated.

In testimony whereof I affix my signature.
